UNITED STATES PATENT OFFICE

HOLDEN W. RIGHTMYER, OF TOLEDO, OHIO, ASSIGNOR TO THE AMERICAN SWISS COMPANY, OF TOLEDO, OHIO, A CORPORATION OF OHIO

DOOR LATCH

Application filed June 23, 1931. Serial No. 546,295.

This invention relates to door latches, as for example automobile door latches and an object is to produce a simple and efficient door latch having the new and improved features 5 of construction, arrangement and operation hereinafter described.

For purposes of illustration, an embodiment of the invention is shown on the accompanying drawing in which:

- 10 Figure 1 is a side elevation of a door latch; and Fig. 2 is a fragmentary view of an alternate form in which a lug is formed on the pull-to handle for engagement with the outer roll back arm.
- 15 The illustrated embodiment of the invention comprises a door latch having a back plate 1 provided with an outwardly bent flange 2 which is formed with an opening through which the nose 3 of the latch bolt 4 is movable. The latch bolt is normally held 20 in projected or latching position by a spiral spring mounted on the back plate and for guiding the bolt a headed pin 5 fixed to the back plate projects through a longitudinally 25 elongate slot 6 in the bolt plate. Assisting in guiding the latch bolt and holding it in spaced relation with respect to the back plate is a plate 7 which is mounted on the pin 5 and has a flanged rim 8 extending part way 30 around the plate.

For retracting the latch bolt from the outside, a roll back 9 is mounted on the back plate and is held in place by a suitable cover plate 10 suitably secured to the back plate as 35 by outwardly bent tabs 11. A spindle-receiving opening 12 is provided in the roll back hub to receive the usual handle-operated spindle shaft. Projecting at an angle from the roll back 9 and secured for movement 40 therewith is an arm 13 having a nose 14^a, the purpose of which will hereinafter appear.

The latch bolt is retracted from the inside by a lever 14 which is pivoted at 15 to the back plate 1 and is provided with an upwardly and inwardly inclined portion 16. The rear end of the bolt is flanged over at 17 at an angle corresponding to that of the handle portion 17. The lever 14 is shown in its 45 normal position in the drawing and it is apparent that movement of the lever to the

right of Fig. 1 operates to retract the latch bolt.

A notch 18 is cut out of the lever 14 on the side away from the flange 17 and provides an abutment 19. When the lever 14 is moved to the left from normal position, the abutment 19 engages the underside of the nose 14^a thereby preventing the latch bolt from being retracted from the outside. Rocking movement of the lever 14 to the left of Fig. 1 is limited by the plate 7. As shown in Fig. 2 a lug 19^a may be employed instead of the notch 18 and provide an abutment for blocking movement of the arm 13. It will be seen that successively upon movement of the lever 14 to the right the outside roll back 9 is released and subsequently the latch bolt is retracted.

A slideable plate 20 guided by pins 21 operated in an elongate slot 22 may be moved 70 by a cam 23 to move the lever 14 out of roll back blocking position. This may be key-controlled, if desired so that insertion of a suitable key and turning same operates to release the outside roll back 9 to enable the 75 door to be opened from the outside.

It is to be understood that changes in details of construction, arrangement and operation may be effected without departing from the spirit of the invention as defined in the 80 appended claims.

What I claim is:

1. A door latch comprising a back plate, a tensioned latch bolt movable over said back plate, an outside operated roll back for reTRACTING said latch bolt, a flange on the outer portion of said latch bolt, a lever pivoted at one end to said back plate and normally disposed in substantially vertical position with a portion thereof lying close to said latch bolt, said lever being engageable with said flange for retracting said latch bolt, an arm fixed to and movable with said roll back, and an abutment on the side of said lever remote from said flange and adapted to be moved 90 into the path of movement of said arm for blocking movement of said outside roll back. 95
2. A door latch comprising a back plate, a tensioned latch bolt movable over said back plate, an outside operated roll back for re- 100

- tracting said latch bolt, a down-turned flange on the outer portion of said latch bolt, a pull-to lever pivoted at one end to said back plate and normally disposed in substantially vertical position with a portion thereof extending beneath said latch bolt, said lever being engageable with said flange for retracting said latch bolt, an arm fixed to and movable with said roll back, and an abutment on the side of said lever remote from said flange and adapted to be moved into the path of movement of said arm for blocking movement of said outside roll back, a slide engageable with said lever and adapted to move same away from blocking position, and cam means operable from the outside for actuating said slide.
- 10 In testimony whereof, I have hereunto signed my name to this specification.
- 15
- 20 HOLDEN W. RIGHTMYER.
